UNITED STATES PATENT OFFICE.

FRANK A. MCGUIRE, OF IOLA, KANSAS.

CUSPIDOR.

1,079,656.

Specification of Letters Patent. Patented Nov. 25, 1913.

Application filed January 2, 1913. Serial No. 739,865.

To all whom it may concern:

Be it known that I, FRANK A. MCGUIRE, a citizen of the United States, residing at Iola, in the county of Allen and State of 5 Kansas, have invented certain new and useful Improvements in Cuspidors, of which the following is a specification.

This invention comprehends improvements in cuspidors and relates more particularly to cuspidors which are particularly adapted for use in railway coaches.

One of the objects of the invention resides in the provision of a spring actuated cover for cuspidors of this type, the 15 cover being provided with a spring-pressed knob, which is adapted to engage the edge of a casing to lock the cover in its open position.

The invention also aims to generally improve cuspidors of this nature to render them more sanitary and commercially desirable.

With these and other objects in view, as will become more apparent as the description proceeds, the invention consists in certain novel features of construction, combination, and arrangement of parts, as will be hereinafter described and claimed.

For a complete understanding of my invention, reference is to be had to the following description and accompanying drawings, in which,

Figure 1 is a top plan view of a section of a car floor, showing my device applied thereto, Fig. 2 is a transverse sectional view taken upon the plane of line 2—2 of Fig. 1, Fig. 3 is a vertical longitudinal sectional view through the car floor and my device, the latter being shown partly in elevation, 40 Fig. 4 is a view similar to Fig. 3, showing the cuspidor in elevation and open, and, Fig. 5 is a transverse sectional view taken upon the plane of line 5—5 of Fig. 1, showing the construction of the spring-pressed 45 knob.

In the following description and accompanying drawings, similar parts will be referred to and designated by like reference characters.

50 Referring in detail to the drawings by numerals, 1 designates a car floor having its upper surface formed with a shallow recess 2. An opening extends through the recessed portion of the car floor adjacent one 55 end of said recess and has positioned therein the neck 3 of a cuspidor. The neck is pro-

vided about its upper edge with an annular flange 4, which rests upon the bottom of the recess 2 and assists in supporting the cuspidor, which latter has a body portion comprising an upper section 5 and a lower or bottom section 6. The lower edge of the upper section 5 is formed with an annular concavo-convex flange 7, which overlaps a bead 8, formed upon the upper edge of the lower section. A hinge 9 connects the two sections and, if desired, a flat metal bow spring 10 may be employed to assist in holding the section 6 in engagement with the section 5.

An ear 11 is formed upon the bottom of the cuspidor and has pivotally connected thereto a link 12, said link being also connected to the lower end of a lever 13. The lever extends upwardly through a recess 14 in the car floor and is pivotally supported upon the member 15. A locking bar 16 is pivotally secured at one end to the upper portion of the lever 13 and engages at its free end a stop block 17, which is rigidly 80 secured to the floor of the car. It will be noted that the block 17 has one of its edges inclined downwardly and inwardly, as indicated at 18, for engagement with the upper edge of the lever 16, said lever being 85 beveled at its free end to provide an intimate contact with the floor. When the members are positioned, as shown in Fig. 3, the bottom section 6 of the cuspidor is held against the upper section 5, but may be 90 swung away from engagement therewith by springing the bar 16 out of engagement with the block 17 and pulling the upper end of the lever 13 against the end of the cuspidor. The recess 14 is formed with an 95 inclined wall 19, which limits the swing of the lever 13 in one direction. A plate 20 is slidably secured upon the under side of the floor 1 by means of the strips 21 and is provided with an opening through which the 100 lever 13 projects. This plate is for the purpose of closing the recess 14.

A plate 22 having one of its ends rounded, is fitted within the recess 2 and is formed with a circular opening 23 directly over the 105 neck of the cuspidor. The plate is formed upon its under side with a marginal flange 24, which extends adjacent the longitudinal edges of said plate and around the curved edge of the same. The flange rests upon the 110 bottom of the recess 2, holds the top of the plate 22 flush with the car floor and is

formed with a groove 25, in which slides a cover plate 26. The cover plate is rounded at one end, so as to completely close the opening 23 when moved into engagement 5 with the curved portion of the flange 24. The cover plate 26 is formed adjacent one end with an upstanding projection 27, which slides within an arch portion 28 extending longitudinally along the center of 10 the plate 22. An expansive spiral spring 29 bears against the projection 27 and the wall 30 of the casing 22 and serves to hold the cover plate 26 normally over the opening 23.

15 A knob 31 is held within a counter-sunk opening in the cover plate 26 by means of a flat metal spring 32 secured to the under side thereof. The knob 31 is formed with a transverse recess 33 in its outer end for 20 engagement with the edge 34 of the arch portion 28, whereby the cover is retained in its open position.

In use lever 13 will be positioned under a car seat and the cuspidor will be disposed 25 in front of the same so as to be in convenient reach of an occupant of said seat. When it is desired to use the cuspidor, the cover plate 26 may be moved from over the opening 23 by kicking the spring pressed projection 31. When it is desired to clean my 30 improved cuspidor, it may be filled with water and then emptied by actuating the lever 13. The spring-pressed knob 31 may be disengaged from the casing plate 22 by 35 a downward pressure upon the former.

It will be seen from the foregoing description in connection with the accompanying drawings, that I have provided a car cuspidor which is extremely sanitary, which is 40 cheap to manufacture and install, which, when not in use, is disposed from view under the car floor, and which may be easily opened and closed by the user.

45 It is to be understood that while I have shown and described the preferred embodiment of my invention, I do not wish to be limited to this exact construction, combination, and arrangement of parts, but may make such changes as will fall within the 50 spirit and scope of the invention.

Having thus described my invention, what I claim is:—

1. The combination with a floor having a recess formed in its upper surface and a transverse opening communicating with 55 said recess, of a cuspidor secured within said opening and projecting below the recess, a plate fitted within the recess and formed with the opening directly over said cuspidor, the plate being formed with a central longitudinally extending arch portion, a cover plate slidably secured to said first mentioned plate and formed with a projection adapted to be received within said arch portion, and a spring seated within said 60 arch portion and bearing against the projection, whereby the cover is normally retained in its closed position.

2. In a device of the character described, the combination with a casing, of a cover 70 plate adapted to slide within said casing, the cover plate being formed with a transverse opening, a knob extending through said opening, and a flat metal spring engaging one end of said knob to normally retain 75 the same in a projected position, the outer end of the knob being formed with a transverse recess to engage one edge of said casing, whereby the cover is retained therein.

3. The combination with a cuspidor, of a 80 casing plate projecting at one end over said cuspidor, the casing plate being formed with an opening communicating therewith, a cover plate slidable within the casing plate and adapted to close said opening, the casing plate being formed with a longitudinally 85 extending arch portion terminating at said opening, means carried within said arch portion for engagement with the cover plate to hold the latter over the cuspidor, and a 90 spring-pressed knob carried by the cover plate for engagement with one end of the arch portion, whereby the cover plate is held from over the cuspidor.

In testimony whereof I affix my signature 95 in presence of two witnesses.

FRANK A. McGUIRE.
